UNITED STATES PATENT OFFICE.

MATTHEW H. LOUGHRISE, OF BOGOTA, NEW JERSEY.

RAILWAY-TRAFFIC-CONTROLLING SYSTEM.

Application filed February 9, 1923. Serial No. 618,156.

This invention relates to a railway traffic controlling system in which traffic on a railroad is controlled according to the spacing of trains on the track, according to speed, and according to the direction in which trains are moving. It is effective on single track where traffic is in both directions and on double track where traffic is in one direction only. This invention includes means whereby a train may be controlled from the leading car or power unit in the train when it runs in either direction and on each portion of a train that may be sub-divided. This invention further contemplates a system for application to single track operation, whereby opposing movements are prevented throughout a section of single track, whereas trains may follow each other closely in either direction. This invention includes certain principles in operation for inductively obtaining effects between the moving train and the track apparatus and includes a mechanism which is gradually driven by the movement of the train over the track to a condition which will make the train control effective unless effects are obtained from the track to overcome this condition. This invention includes certain novel features in the construction of the track magnet, in the construction of a friction drive, in the construction of a driven mechanism for controlling the train, and in the application of the circuits both on the locomotive and on the track. These and other features of the invention will be more fully understood from the following specification and the accompanying drawings in which Figs. 1, 2 and 2^a show a novel type of friction drive used with this invention, Fig. 3 shows the driven mechanism, Figs. 4, 5, 6 and 7 are details of the mechanism shown in Fig. 3, Figs. 8 and 9 show the details of construction used in the track magnet, Fig. 10 shows the arrangement of wiring that may be used on the locomotive, including cab-signals, Fig. 11 shows a wiring diagram that may be used for double track operation, Fig. 12 shows a wiring diagram suitable for single track operation and Fig. 13 shows an arrangement suitable for suspending the operation of the system on multiple unit trains.

A considerable portion of this invention was included in application Serial No. 47,206, filed August 24, 1915 now Patent 1,299,595. In this application certain developments and improvements are incor-

porated which have been made since that time.

This invention contemplates the use of a mechanism which is driven by some part of the running gear of the locomotive and which at certain points on the track is influenced by clear track or blocked track conditions, to control the train as desired. I will describe the mechanism for this purpose first, which includes a novel type of friction drive and a novel type of mechanism responding to this friction drive which is designed to take care of the operating conditions to be found on a railroad.

The friction drive is illustrated in Figs. 1, 2 and 2^a in which 11 is the running rail of a railroad track, 12 is a locomotive wheel preferably a wheel not connected with the driving mechanism, 13 is the wheel axle and 14 is the frame of the friction drive supported from the axle box. 15 is the head of this frame which by means of the shaft 16 pivotally supports a pair of arms 17 and 18. The arm 18, it will be noted from Figs. 2 and 2^a terminates in a sleeve 19 in which the bushing 20 rotates and through this bushing the shaft 21 is splined at 20^a so as to be moved by the action of coil spring 22. On shaft 21 is mounted the friction wheel 23 and the spur gear 24 is mounted on sleeve 20. Wheel 23 is held against the running wheel 12 by the coil spring 23 which is arranged in compression as shown. As wheel 12 rotates, therefore, wheel 23 rotates with it, carrying shaft 21 which in turn rotates bushing 20, carrying the spur gear 24 which meshes with the gear 28 on shaft 16. This shaft in turn carries the worm 29 engaging the worm wheel 30 on the shaft 31 to which the flexible connection 32 is attached.

It will be noted that a pair of similar friction wheels is provided, movable about shaft 16 as a centre. Wheel 25, mounted on shaft 26 is held against the running wheel 12 by spring 34 acting through arm 17. Shaft 26 carries a spur wheel 24^a which meshes with the spur wheel 28 so that the pair of friction wheels 23 and 25 cooperate to drive the spur wheel 28. There are certain advantages secured by this construction which may be enumerated as follows:

By providing a pair of friction wheels operating independently, one of these wheels will maintain the drive in case the other wheel should become broken off. A pair of wheels provides a more positive drive than

is obtainable with one wheel alone. The running wheels of a locomotive develop flat spots which cause a variation in the friction between the running wheel and the friction wheels, tending to produce a non-uniform drive. In this invention the friction wheels are kept pressed tight against the running wheel by the springs 33 and 34 and irregularity in driving is reduced. The arms 17 and 18, moving about a centre parallel with the axle of the running wheel are automatically adjusted to provide for any irregularity of this kind. By providing a longitudinal movement for the axes of the friction wheels 23 and 25, any side play of the locomotive wheel relative to the supporting frame is automatically taken care of and the friction wheels themselves always bear upon the tread of the wheel close to the flange and thus, although the locomotive wheels are conical, a uniform friction drive is obtained. The surface of the friction wheels may be provided with a fibrous material 23^a to increase the co-efficient of friction between the running wheels and these wheels as indicated in the drawings.

The controlling mechanism on the locomotive is driven from the friction drive just described by the flexible connection 32, Fig. 3, connecting to shaft 36, rotating in frame 37 and carrying the centrifuge 38 which acts against the spring 39 and moves the collar 40 according to speed. The collar 40 operates a bent lever 42, pivoted at 41 and arranged to interrupt or establish one or more circuits as shown at 43 and as more fully described hereafter in connection with the operating circuits.

The upper end of shaft 36 connects to worm 44 engaging worm wheel 45, Fig. 4, which in turn rotates shaft 46. This shaft has the disks 47 and 52 keyed thereon and which rotate therewith. Between these disks is placed the disk 48, Fig. 5, which is loosely mounted on shaft 46 and has an insulated arm 49 which makes contact with 50 or 51, depending upon the direction in which it rotates. In the operation of the circuits hereafter described, this arrangement may be provided to control a number of circuits. The disk 48 is held in frictional engagement with the disks 47 and 52 by means of corrugated spring disks 48^a placed between these disks, with the result that as disks 47 and 52 move in a certain direction, the disk 48 is carried therewith until stopped by the contact point 50 or 51. This disk, therefore, is responsive to direction and will make contact between 50 or 51, depending upon the direction of rotation of the running wheel 12.

The outer side of disk 52 carries a pin 53 which engages groove 55 in disk 54 as illustrated in Fig. 6. This groove it will be noted, is circular and may pass around the

greater part of the circumference of disk 54. The result is that pin 53 will ride idly in groove 55 until it comes to the end thereof after which disk 54 is rotated in unison with disk 52. This groove is provided so that a locomotive may back up, thereby moving the pin 53 backwards in groove 55 for a limited distance and resume its normal running direction without changing the condition of the controlling apparatus.

The shaft 46^a rigidly connected with disk 54, carries the spur wheel 57 engaging with the idler wheel 58 which in turn engages the idler 59 which drives the spur wheel 60 on shaft 61 as shown in Fig. 7. When the spur wheels are in the position shown in Fig. 7, the shaft 61 rotates in the reverse direction to shaft 46. If, however, the frame 56 arranged to rotate on shaft 46^a and carrying the idlers 58 and 59, moves to the right, (as seen in Fig. 7) so that spur wheel 59 is disengaged from and spur wheel 58 engages spur wheel 60, then the direction of rotation of shaft 46^a is the same as shaft 61. The movement of frame 56 is obtained by a corrugated spring member 63, between disks 62 and 64. Disk 64 is keyed to shaft 46^a and disk 62 forms one side of the frame 56 which is loosely mounted on shaft 46^a. This insures that when shaft 46^a begins to rotate in the counterclockwise direction (Fig. 7), it will swing frame 56 to the right (as viewed from Fig. 3), causing idler 59 to engage spur wheel 60 so that shaft 61 will rotate in the direction opposite to that of shaft 46^a, that is in the clockwise direction. When shaft 46^a begins to rotate in the clockwise direction it will swing frame 56 to the left (as viewed from Fig. 3), causing idler 58 to engage spur wheel 60 so that shaft 61 will rotate in the same direction as 46^a, that is in the clockwise direction. From the above it will be seen that whatever may be the direction of rotation of shaft 46^a the rotation of shaft 61 will be unidirectional. It is understood that there are several methods of obtaining a unidirectional drive from a shaft which may rotate in either direction and which are suitable for the present invention, the object of which is to insure that the controlling mechanism shall always move in uniform direction when the locomotive runs either backwards or forwards.

The shaft 61 is provided with a friction clutch 65 having an inner clutch member 67 held in engagement by the spring 66. This clutch may be disengaged by the magnet 70 operating lever 69 on pivot 68 and having a jaw to release the clutch 65 as shown. This friction clutch disconnects the controlling mechanism when not in service or when it is desired to make adjustment. The controlling mechanism on shaft 61 may consist of an insulated drum 71 having certain contact

plates engaged by the contact fingers 73, also the insulated drum 72 having certain contact plates engaging the contact fingers 74 or may be arranged to operate any other type 5 of train control or may have an increased number of contacts as required by the circuits hereafter to be described.

The reduction obtained from worm 44 it 10 will be noted, causes shaft 46 to revolve at a low speed. This reduction, however, may be applied to shaft 46^a or shaft 61 if quick action is desired in some of the functions just described.

15 *The track magnet.*

The track magnet is illustrated in Figs. 8 and 9, and consists of a magnet designed to be clamped against the side of a standard railroad rail, without drilling or preparation of the rail for this purpose, so that it 20 may be quickly clamped in place and removed. This construction provides a close air gap on one pole and admits of the air gap on the other pole being increased to 25 increase the clearance between the locomotive and the track. This device consists of a bracket 81 clamped to the rail 11 by the U-bolts 82 which also clamp the nonmagnetic bracket 84 supporting the pole piece 30 of the track magnet as indicated at 85. The bracket 81 supports the vertical plate 83 adjacent the head of the rail and forming one pole of the track magnet. A bolt 88 passes from the plate 83 to the plate 87 and forms 35 the core for the magnet coil 86. The plate 87 may be riveted or bolted to the vertical leg of the angle 85. A magnetic field is produced between the plate 83 and the angle 85, when the coil 86 is energized. The bracket 40 84 may be of brass or other non-magnetic material and is offset as shown, to support the angle 85. It will be noted that the plate 83 is in contact with the head of the rail which practically forms an extended 45 pole piece for this plate and thereby lessens the reluctance of the air gap between this pole and the locomotive device which can be carried close to the rail head. It is preferable that the bracket 84 be placed between the ties and that the energizing coil 86 be placed over the ties, although this is not essential. One or more coils 86 may, of course, 50 be used to provide an extended magnetic section on the track member and the ends may be ramped off as indicated, to avoid causing obstructions. This construction in 55 a track magnet, enables the entire structure to be built in a manufacturing establishment and quickly installed simply by clamping 60 onto the rail, without drilling or other preparation and at the same time maintains the various parts in alignment with the rail itself.

65 It should also be noted that magnet coils, pole pieces or any part of the track mag-

net structure, can readily be replaced without impairing the remainder of the structure.

The locomotive wiring.

The operating circuits and the arrangement of the apparatus on the locomotive will be understood from Fig. 10, showing a complete lay-out including a three-indication 70 cab signal, a brake operating device, an arrangement for cutting the system out of service and a device for transmitting signals from the locomotive to the track controlled by the direction in which the vehicle runs.

The cab-signal is of the light type as indicated by 101 and is controlled by block 80 relays 102 and 103. These relays are in turn energized by the track magnet and are de-energized at intervals as the train proceeds along the track, by the operation of the mechanism as indicated at 71. The block 85 relays are in turn controlled by secondary block relays or stick relays 104 and 105, also controlled by the operating mechanism as indicated at 72. A cut-out relay 106 is provided and a brake valve 107 and certain apparatus on each side of the locomotive, which 90 is inductively influenced by track devices hereafter to be described.

When the locomotive core 111 passes over the poles 83 and 85, of the track magnet, with the coil 86 energized, by direct current, there will be a momentary current generated in the circuit, including wires 112 and 113 and the pick-up coil 114 of relay 104. This coil will momentarily energize and pick up 95 relay 104, closing the circuit through the top contact finger from wire 120 to wire 121 and by means of the contact 122 this circuit is maintained through the rotating drum 72, thus causing relay 104 to remain energized 100 while the contact 122 engages a metallic section of the drum 72 and also interrupting this circuit, thereby causing this relay to become deenergized, when the contact 122 passes over a section of insulation. It is 105 here pointed out that in the developments of the circuits both for the locomotive and track apparatus, the battery wire is indicated by B and the other side of the battery or common wire is indicated by O, in preference to connecting up these wires, with the object of simplifying the diagram.

Relay 104 is also energized by another means, including magnets 115 and 116. These magnets are independently pivoted on 110 the same axis at 117 and it will be noted that their poles are reversed, that is to say, on the top magnet the S pole is pointing downward, while in the magnet 116 the N pole is pointing 115 downward. The lower ends of these magnets pass in a vertical plane between the poles 83 and 85 of the track magnet and if this magnet is deenergized, these poles naturally remain by gravity in the vertical position, but if these poles are energized, then 120 125 130

the magnets are deflected, depending upon the polarity of the track magnet. If, for instance, in the specific embodiment shown at the left, the pole 83 of the track magnet shown in detail A is energized, with N polarity and the pole 85 with S polarity, then magnets 115 and 116 will be deflected as shown. In this condition it will be noted that a circuit is established by magnet 116 5 from battery to wire 118 and by magnet 115 to wire 119 and wire 120 to relay 104, thereby energizing this relay and establishing a holding circuit through the front contact which maintains it energized through the 10 contact finger 122 as previously described.

The operation just described provides two means for picking up relay 104, the first by an inductive impulse from the track magnet and the second by the movement of polarized magnets under the influence of the track magnet. This secures the following advantages: the inductive influence from the track magnet when it is energized by direct current consists of a single impulse, the force of 15 which is proportional to the speed with which the lines of force in the magnetic field are cut by the magnetic yoke 111, that is to the speed of the train so that devices operating inductively on this principle, while 20 effective at high speed, are practically ineffective at low speed and alone, are not suitable for establishing a signal on a locomotive to show the condition of the block without regard to speed of the train. The moving magnets or armatures on the other hand, change position by mechanical motion and, 25 therefore, require an appreciable time for their operation. These armatures are constructed comparatively rugged and, therefore, have considerable inertia. When a 30 train runs at high speed it may pass over the track magnet, which may consist of not more than two or three coils, without allowing a sufficient time interval for these 35 magnets to change position. In this case, conditions are established for energizing relay 104 inductively without requiring the operation of these magnets. On the other hand, when the train moves slowly the inductive impulse is practically negligible and a time interval is provided which enables the polarized magnets to change position and, thereby secure the proper operation of 40 relay 104. When the locomotive passes 45 away from the influence of the track magnet the magnetic yoke 111 is, of course, deenergized, magnets 115 and 116 resume the vertical position by gravity, and thereby interrupt the circuits which they established when 50 passing over the energized magnet. It is, of course, apparent that if the track magnet were energized by alternating current, the inductive effect in coil 114 would be sustained and the use of magnets 115 and 116 55 could be dispensed with. Also, if slow op-

eration only is to be considered with track magnets operating on direct current, the use of the magnetic yoke 111 may be dispensed with.

Magnets 115 and 116 have their pivots 70 parallel to the line of track and having considerable mass, would be subject to displacement by centrifugal force when a locomotive was running on a curve, although, of course, a large part of this condition may be compensated for by proper counterweighting. In order, however, to guard against the possibility of these magnets moving in a direction to give a false clear signal from centrifugal action, I provide them in duplicate and 75 arrange that the circuit established by these magnets shall require one magnet to move in one direction and the other to move in the opposite direction as indicated in the drawing. If these magnets should move together 80 in the same direction, it will be noted that no circuit is established by them to interfere with the operation of the system.

The operation that has just been described in detail, relative to relay 104, is duplicated 90 on the right-hand side of the drawing, relative to relay 105 having corresponding parts and circuits similarly lettered and operating in exactly the same manner.

When the relay 104 is energized, a circuit 95 is established through the second contact finger from battery to wire 123 which by wire 124 energizes the block relay 102. This relay has a holding circuit through its front contact and by wire 125 to contact finger 100 126 and rotating drum 71 as shown; relay 105 controls block relay 103 in exactly the same manner by a circuit having similar reference characters. The block relays control the light signal 101, providing a green or 105 proceed indication, controlled by wire 132, contact of relay 102 energized, wire 131 and contact of relay 103 energized, which latter contact is connected to battery. When both 110 of the block relays are energized, a proceed signal is displayed. A yellow or caution signal is displayed when one of the block relays is energized and the other deenergized. This signal is controlled by wire 134, relay 102 energized, wire 135 and relay 103 115 deenergized, the armature of which relay is connected to battery or by wire 134, relay 102 deenergized, wire 133 and relay 103 energized. A red signal is displayed when both relays are deenergized. This signal is controlled by wire 137, relay 102 deenergized, wire 136 and relay 103 deenergized, the armature of which relay is connected to battery. This arrangement is more fully described in United States Patent No. 1,299,595, 120 dated April 8, 1919.

The common side of the circuit controlling signal 101 is controlled by wire 153 through a contact on the cut-out relay 106 125 deenergized, so that when the system is cut- 130

out or suspended the light signal is also extinguished. The brake controlling mechanism is controlled by magnet 107, wire 139, block relay 103 energized, wire 138 and block relay 102 energized the armature of which relay is connected to battery so that when the track is clear this mechanism is held inoperative. It is also held inoperative through the circuit established by wire 140 and contact 141, controlled by the arm 42 operated by the centrifuge 38 so that when the speed is below a predetermined value this mechanism is held inoperative. There are various ways of applying train-control and this arrangement is simply typical of a number which may be adopted in carrying out this invention. The brake mechanism is also held suspended by a circuit established through wire 142 and the cut-out relay 106 energized.

The cut-out system.

In the operation of a system of this kind and particularly a system that has a continuous driven mechanism, it is desirable that its operation may be suspended or cut-out of service when a train moves over a portion of track where this system is not in use. For this purpose a cut-out relay is provided which energizes the declutching magnet 70, thereby suspending the operation of the controlling drums until the mechanism is brought into operation again. The cut-out arrangement is operated by relay 106 which, when energized, suspends the operation of the moving mechanism, extinguishes the light signal and holds the brake valve inoperative. This cut-out is operated by a signal transmitted from track magnets on both sides of the track having a predetermined polarity, usually opposite to the polarity required for operating the block system. For instance, if the polarity of the track magnets 86 on each side of the track is reversed so that the polarity of 83 and 85 is reversed, then the magnets 115 and 116 on both sides will swing into the opposite position from that shown. This will set up a circuit from battery through magnet 116 on the right, wire 146, magnet 115, wire 147, magnet 115 on left, wire 148, magnet 116 and wire 149 to relay 106. When this relay is energized, a holding circuit is established through the first contact to wire 151 through relay 104 deenergized, wire 152 and relay 105 deenergized, to battery, that is to say, when relays 104 and 105 are deenergized, the holding circuit for relay 106 is established and it remains energized. On the other hand, when either of relays 104 and 105 is energized as occurs at each energized ramp, the holding circuit of relay 106 is interrupted, this relay is deenergized and the system becomes operative again. It should be noted that the pick up circuit of relay

106 controlled by magnets 116 and 117 is closed only while these magnets are deflected and this circuit is interrupted when these magnets resume their vertical position. It will be noted that it requires energized track 70 magnets on each side of the track to energize the cut-out relay. The energy in these magnets will, of course, energize coils 114 and normally energize relays 104 and 105. However, these track magnets are considerably longer than the regular track magnets and provide a prolonged impulse which moves the magnets 115 and 116 even when the speed of the train is comparatively high. After the impulse in coil 114 has died out, so relays 104 and 105 are deenergized as it is assumed that the stick circuit through 122 is not established at this time. It should also be noted that ordinarily when a train takes a side track, the speed is reduced to a low value.

For certain operations of the track apparatus, it is desirable to give a signal from the locomotive to the track. This has been provided for inductively in the present arrangement which includes a transformer 161 on the locomotive, from which a circuit is established through wire 162, contact 51 on disk 48 when moved to the right contact 51, wire 163, coil on core 164, returning through wire 165 to the transformer. Consequently, when the locomotive is running in one direction, the core 164 is energized by alternating current. When the locomotive is moving in the opposite direction a circuit is established from the transformer 161 through wire 162, contact on disk 48 moved to the left contact 50, wire 167, coil on core 166, returning by wire 165 to the transformer, thus energizing core 166. These cores 164 and 166 are selectively energized, depending upon the direction in which the locomotive is running. When a core similar to 164 and 166, energized by alternating current, runs over a track magnet similar to A, having a coil 86 leading to a circuit, it is apparent that an alternating E. M. F. will be transmitted to this circuit which in turn may be used to operate certain elements of the block system on the track hereafter to be described in connection with single track operation.

The track wiring.

The track wiring for double track operation, that is where train movements are always in the same direction, is illustrated in Fig. 11. This track is divided into sections or blocks indicated by the letters *a*, *b*, and *c*, separated by the insulated joints 203. Each block section is provided with a track battery 204 and at the opposite end a relay 205 is connected as shown by the dotted lines, the relays being marked 205^a, 205^b and 205^c to correspond with the lettering of the block sections. This, it will be noted, is a con-

ventional track circuit and is shown here as a method of determining when the track is clear and when it is blocked, that is extensively in use, although the invention may 5 be applied by using other means than the track circuit for this purpose.

Convenient to the entrance to each block, the track magnet 206 is placed on one side of the track, having an energizing coil 207 10 connecting by wire 208 to battery through relay 205 energized, also a track magnet 209 on the opposite side of the track having a coil 210 connecting by wire 211 through relay 205 energized, for the first block to wire 212 and through the track relay for the next 15 block to battery, all locations being wired alike and having corresponding reference characters. When two blocks ahead of the track magnets are clear, it is apparent that 20 both these magnets are energized and when only one block is clear magnet 207 will be energized and magnet 210 will be deenergized. When the first block ahead is occupied 25 then both these magnets are deenergized.

Consider now the progress of a train equipped with apparatus as contemplated in this invention and assume that the track is clear. As the train proceeds through the 30 block it will be noted that the rotating drum 71 will interrupt the holding circuit of the block relays 102 and 103, also the rotating drum 72 will interrupt the holding circuit 35 of relays 104 and 105. A quarter rotation 40 of the drum 72 will deenergize the relays 104 and 105. The relation of the track magnets to the position of the contacts on these rotating drums is such that when the track is clear an impulse is transmitted to energize the relays 104 and 105 at a time when the holding circuit may be established. For instance, a train on entering a clear block receives an impulse through the core 111 45 which picks up relay 104 on the one side and 105 on the opposite side. When these relays are picked up a circuit is established through the contact segment in the position shown, but as the train proceeds the contact segment moves from under the contact finger 122 and interrupts the holding circuit just 50 described, permitting relays 104 and 105 to become deenergized. This condition may occur when the train has traveled about half the distance through the block. However, it 55 will be noted that the insulated segments on the drum 72 are shorter than the contact segments on the drum 71 and arranged to overlap them in position so that before drum 72, rotating at the same speed as drum 71, has 60 deenergized the relays 104 and 105, the holding circuit through the contact finger 126 is established by drum 71. This permits the train to continue through the block until 65 the next set of track magnets is encountered when the drum 72 is moved into position.

again so that the holding circuit for the stick relays 104 and 105 may be established as soon as these relays are energized from another track impulse. This condition being maintained for clear track will result in 70 holding the block relays 102 and 103 energized and give a clear signal. Suppose now, that a track location is encountered in which one of the track magnets is energized and the other is deenergized, then either one 75 of relays 104 or 105 will not be picked up but will remain deenergized and as the train proceeds and interrupts the holding circuit of the block relays 102 and 103, one of these 80 relays will become deenergized and remain deenergized until another impulse is received from the track, thus establishing a caution signal. If now, another track location is encountered in which both of the 85 track magnets are deenergized, then there 90 will be no impulse to pick up relays 104 and 105 with the result that these relays remain deenergized and both of the block relays 102 and 103 become deenergized when the drum 71 has moved around to interrupt the holding 95 circuit, thereby giving a stop signal.

Ordinarily with any control system of this type, it is necessary to provide blocks of equal lengths. With the arrangement just described, however, this condition is not necessary, as considerable latitude may be allowed in arranging block lengths, either greater or less than the distance represented by the movement of the controlling drums. For instance, the holding circuit of the relays 104 and 105 is effective during a ninety 100 degree movement of the drum 72 and if the track devices are encountered during the time that the train is traveling over a portion of track represented by this ninety degree movement, it is apparent that the apparatus will operate properly. The track magnets may be located some distance from the beginning of the block if desired in order that the relays 104 and 105 may be operated 105 before the train has proceeded any great distance into the block. 110

In the section D shown to the right, a turn-out is illustrated with a means for suspending the operation of the locomotive apparatus. This arrangement consists in placing a track magnet on each side of the track having on one side an outer member 215 energized by the coils 214 with a N. polarity and on the opposite side a member 216 energized by the coils 217, also with N. polarity. This polarity is in the opposite direction to the polarity of the track magnets 206 and 209 used for giving the block indication. The magnets 215 and 216, therefore, will 120 change the position of the magnets 115 and 116 on the locomotive and establish the circuit for energizing the cut-out relay 106 and thus suspend the operation of the apparatus until the locomotive reenters the sig- 130

naled territory. In this connection it will be noted that the magnets 215 and 216 should be located a sufficient distance from the last set of magnets so that the drum 72 will have moved a sufficient distance to interrupt the holding circuits of relays 104 and 105.

The application of this arrangement for single track operation is illustrated in Fig. 12, that is where train movements are in both directions on the same track. This arrangement provides an absolute block protection against opposing movements between the sidings on a portion of single track and at the same time provides for following movements with a train spacing according to the block arrangement. In this installation the track may be divided into sections or blocks as indicated by *a*, *b*, *c*, *d*, *e*, *f*, *g*, *h* and *j*. The portions *b*, *d*, *f* and *h* are about equal in length to the standard length of block. The portions *a*, *c*, *e*, *g* and *j* opposite the track magnets are short track sections and are arranged to be included in the block system ahead of the train when the train runs in either direction. Each section is provided with a track battery as indicated at 204^a and a track relay as indicated at 205^b, the track relays being lettered *a*, *b*, *c*, *d*, *e*, *f*, *g*, *h* and *j*, to correspond with the portions of track similarly lettered. For the sake of simplicity connections to the track for these relays have not been shown. Directional control relays 221 are provided at each track magnet location for traffic from left to right and directional control relays 222 are provided for traffic from right to left. A relay 221, for instance, opposite section *a*, is controlled by wire 223, track relay *b*, wire 224, track relay *c*, wire 225 and relay 221 at location *c* the armatures of which are connected to battery. Relay 221 at location *e* is controlled by a circuit similarly lettered through track relays *d* and *e* and relay 221 at location *e*. Relay 221 at location *e* is in turn similarly controlled by track relays *f* and *g*, and relay 221 at location *g* is similarly controlled by track relays *h* and *j*. It will be noted from this arrangement that if a train enters upon section *j* and deenergizes relay 221, at location *g*, this will in turn deenergize all the directional relays 221. This will set the signal 258 at the opposite end of the section controlled by wire 257 to the stop position and will also deenergize coil 207 of the track magnet for section *a*, so that a train cannot enter the track from this direction without receiving a stop signal and it will be noted that this condition is maintained while the train proceeds through the entire single track section. This is known as the absolute block for head-on protection. For traffic in the opposite direction a similar operation is required relative to relay 222 at section *j*. This relay is controlled by wire 227, relay *h*, wire 228, relay *g*, wire 229, and

relay 222 at *g*, the armature of which connects to battery. Relay 222 at location *g* is in turn controlled by wire 227, track relay *f*, wire 228, track relay *e*, wire 229 and the armature of relay 222 at location *e* to battery and so on throughout the remaining block sections. If a train, therefore, enters upon section *a*, relay 222 at section *c* is deenergized. This causes the other directional relays 222 to become deenergized and to remain deenergized while the train is proceeding in this direction. This deenergizes wire 257' setting signal 259 in the stop position and deenergizing the track magnet opposite section *j*.

When a train, moving say from left to right, enters a portion of track, it is desirable that another train should be able to follow the preceding train as closely as the block system will permit. For instance, when the rear of the first train has cleared section *c*, it would be good practice to permit a following train to enter at section *a* and when the first train had cleared section *e*, it would be satisfactory to permit a following train to enter section *c*. This arrangement, I secure by a signal transmitted from the train to the track apparatus in combination with the wiring arrangement as shown. For this purpose stick relays 237 are provided for traffic from left to right and stick relays 238 are provided for traffic from right to left. The stick relay 237 opposite section *d* is energized when the track relay *d* is deenergized and when an impulse is transmitted to wire 232 through the coil 233 which may be similar to the magnet coils 86, forming part of the track magnet. When the head of a train reaches section *e*, the rear end will have cleared section *c* as the block is usually of a length greater than the train, and track relay *d* will be deenergized. An impulse is transmitted to coil 233 from the impulse device on the locomotive which impulse is transmitted through wires 232 and 231, picking up relay 237 at *d*. A holding circuit is provided for this relay through wire 239, relay 221 deenergized, wire 240 to the armature of the track relay for section *c* energized. When the stick relay 237 is energized, a circuit is established from battery to wire 226, and wire 225, energizing the directional relay 221 at location *a* and thereby energizing the track magnet for section *a* and permitting a following train to enter the block. When the first train reaches section *g*, an impulse is transmitted to coil 233 which by wires 232 and 231, picks up relay 237 at this location and a holding circuit is established through wire 239, armature of the directional relay 221 deenergized, wire 240 and armature of the track relay *e* energized. When this relay 237 is energized a circuit is established from battery to wire 226, wire 225

225, picking up the directional relay 221 at location *e* and permitting a following train to enter the block at that point or at point *a*. This relation is maintained between any 5 number of following trains.

In the opposite direction the arrangement is similar to that described, except that the energizing coil is placed on the opposite side of the track as indicated at 236 and by 10 means of wires 235 and 234, picks up relay 238 through the back contact of the adjoining track relay. Relay 238 has a holding circuit through wire 241, back contact of armature of the directional relay 222 and 15 wire 242 to battery through the armature of the track relay for section *g*. A similar arrangement is provided for the operation of the stick relay 238 for the succeeding blocks.

It will be noted that the holding circuit 20 for each stick relay is controlled by the preceding directional relay deenergized and by the preceding track relay energized. The track relay control immediately deenergizes the stick relay as soon as a train has encountered 25 the corresponding section and each directional relay control immediately deenergizes the corresponding stick relay when the normal conditions of the block are restored; thus the system is self-restoring 30 from any condition.

The stick relays for the opposing directions cannot be held energized at the same time. The coils for picking up the stick relays are energized by means of the magnetic cores 164 and 166 on the locomotive. If the locomotive is running from left to right the circuit controller 48 will establish the circuit of the core passing over the track magnet on the right side of the track and will 35 deenergize the core on the opposing side of the track so that this releasing impulse can only be received on one side of the track, that is, for one direction of traffic as the locomotive proceeds through the block. When the locomotive returns in the opposite 40 direction with the same end leading, the cores have changed position relative to the track and the energizing coils on the opposite side are operated. If a locomotive should enter a block for a certain distance and then back-up, the change-over arrangement 45 would change over the energizing coil from one side of the track to the other and thus establish normal conditions when the locomotive runs in either direction with either end leading on single track.

This change-over arrangement selectively 50 operates the block system from the direction in which the locomotive runs. However, it should be noted that the system is selectively 55 operated by the track arrangement as the impulse from coils 233 or 236 is controlled by the track relay deenergized for the adjoining block and as this relay is only deenergized for the block which the train occu-

pies it is apparent that the coil controlled by the other track relay will not pick up the stick relay. Connections for coils 210, giving the distant indication on the opposite side of the track, Fig. 12, are for simplicity not shown. These coils are selectively controlled similarly to the coils 207 by the directional relays 221 and 222 and overlapped according to standard practice. For instance, the coil 210 opposite section *e* 70 when traffic is established from right to left should control up to section *a* and when traffic is established from left to right it should control up to section *j*. Coil 210, therefore is controlled by the armatures of 75 relay 221 and 222 over these sections. From relay 221 at section *e* this control is continued to relay 221 at section *g* where it connects to battery. This secures the necessary 80 control through the intervening track sections. The control through relay 222 at section *e* is continued through relay 222 at section *e* to battery, thus securing the necessary 85 track circuit control and the directional relays secure selectivity. The indicator 90 shown in detail B', Fig. 10, on the end of shaft 61, shows the approximate speed of the vehicle and the distance necessary to clear a block. Attention is called to the fact that in most cases in the present invention, when relays are used, electric "flippers" may be substituted as described in application, Serial No. 516,945, filed November 22, 1921.

The cut-out system on multiple unit cars. 100

When this system is applied on multiple unit trains or on trains having more than one locomotive, the usual practice is to control the train from the leading motor car or locomotive and therefore, it is desirable that 105 the operation of the system be suspended on the other motive units. It is also desirable when the various motive units in the train are separated, that the system should become operative on each portion of train thus 110 divided. These conditions are fully met automatically by the arrangement disclosed in Fig. 13, in which M, N, O and P represent the cars or portions of a multiple unit train, each portion having an independent source 115 of motive power. This train is shown as running in the direction indicated by the arrow, and, therefore, the train should be controlled from the car indicated by P and should not be controlled by the other cars. If the direction of the train is changed, then 120 the control should become effective in the car indicated at M and become ineffective on the other cars. If the train is separated into two portions for instance, between N and O, and running in the direction indicated by the arrow, then the control should become effective in the cars indicated by P and N and if the train becomes separated 125 with one portion moving in the direction in-

dicated by the arrow and the other portion moving in the reverse direction, then the system should be operative in cars indicated by P and M.

- 5 Referring to the drawing, 275 represents a circuit controller operated by the couplers of the cars indicated at 276. When the cars are coupled together the circuit controllers 275 are closed as indicated in the drawing 10 and when the cars are uncoupled, these circuit controllers are open as indicated at the end of cars P and M. The circuit controller 279 is operated by the disk 48 on the rotating shaft according to the direction in which 15 the train is moving. When moving as indicated by the arrow, it will be noted that in car M for instance, a circuit is established from battery 280 through circuit controller 279, wire 277, controller 275 on coupler and 20 wire 281 to magnet 70. The circuit of magnet 70 being closed, this magnet declutches the controlling mechanism in this car and renders the system inoperative. It, of course, should be noted that the relay 106 25 may be substituted for the magnet 70 if desired. A circuit is established in cars N and O, similar to M, so that magnet 70 in each car remains energized and, therefore, declutches the operating mechanism. In car 30 P, however, it will be noted that the circuit controller 275 is open. Therefore, magnet 70 is deenergized and the controlling mechanism is driven by the movement of the car to control the train.
- 35 If the direction of the train is reversed so that M becomes the leading car of the train, then each of the circuit controllers 279 is changed to the opposite side so that a circuit is established from battery 280 through circuit controller 279, wire 278, circuit controller 275 in the opposite end of the car and wire 281 to declutching magnet 70. The circuit controller 275 at the left end of cars N, O and P is closed and therefore, the system is inoperative in these cars. In car M, however, this circuit controller is open and, therefore, the mechanism in this car becomes operative to control the train. Now, if the train should break apart, say between N and O, then the circuit controller 275 to the right in car N will be open and to the left in car O will be open. The mechanism in car N, therefore, will become effective to control the rear portion of the train, while it moves to the right. Now, if the train should separate as before, between cars N and O and the cars O and P move in the direction indicated by the arrow and the cars M and N move in the opposite direction, then the conditions will 60 be established similar to those already described, whereby car P will control the portion of train to the right and car M will control the portion of train to the left, that is to say, each leading end of a portion of train automatically becomes effective to control the

train according to the block system and control is automatically suspended when these portions are coupled together forming a unit which is always controlled by the leading vehicle.

With this system it will be noted that the progress of a train along the track tends to establish conditions at intervals which will stop the train or bring the controlling mechanism into operation, unless a proceed signal is obtained from the track to set up conditions whereby this controlling mechanism is rendered ineffective in controlling the train for another portion of track. A friction driven mechanism is provided for operating this controlling mechanism so that each time it functions a definite portion of track is thereby represented, but a considerable variation is provided in the location of the track apparatus cooperating with this mechanism. The system provides for a controlling mechanism continuously rotating in one direction and which is not reset or moved backwards in its operation. It should be noted that if the control segments on drums 71 and 72 were uniform in size, these drums would control the block relays similarly, without regard to the direction in which the drums rotate. However, if the contact segments are longer in one portion of the drum than the other, it would be necessary to rotate these drums continuously in the same direction in order to obtain a uniform control system when the locomotive runs either backwards or forwards. A train may 100 back-up within a block and then proceed in the forward direction again without changing the conditions of the block apparatus, but due to the slot 55 and the mode of operation of 61 a train cannot continue to back-up through several blocks without bringing the system into operation for the reverse running direction. The proceed signals are as contemplated, transmitted by induction between the track and locomotive apparatus and these signals are arranged to be operative through a varying range of speed. However, it is apparent that a contacting method may be used for this purpose or a mechanical method as desired.

Having thus described my invention, I claim:

1. In a system of the class described, the combination of a track with a vehicle thereon having a controlling mechanism, means on said track affecting the control of said mechanism, said mechanism comprising a rotating element driven by the movement of said vehicle on the track and a device having a limited movement operated by friction for causing said element to move in one direction when said vehicle runs in either direction.

2. In a system of the class described, the combination of a track with a vehicle there-

on having a controlling mechanism, means on said track affecting the control of said mechanism, said mechanism comprising a rotating element driven by the movement of said vehicle on the track and a second rotating element connected with the first element by a lost motion connection.

3. In a system of the class described, the combination of a track with a vehicle thereon having a controlling mechanism, means on said track affecting the control of said mechanism, said mechanism comprising a rotating element driven in a predetermined direction by the movement of said vehicle on the track, and a second element driven by the first element through a lost motion connection which lost motion is effective only when the vehicle changes its direction of running.

4. In a system of the class described, the combination of a track with a vehicle having a controlling mechanism, comprising an element driven from the movement of said vehicle and frictional means for controlling the direction of drive so that said element moves only in one direction while the vehicle may move in either direction and means on said track for operating said mechanism.

5. In a system of the class described, the combination of a track with a vehicle thereon having a controlling mechanism, means on said track for operating said mechanism, said mechanism comprising an element driven by the movement of said vehicle on the track, a frictionally operated member embodied in said mechanism and having a limited free movement and a plurality of circuits, said frictionally operated member establishing one of said circuits when said vehicle moves in one direction and establishing another circuit when the vehicle moves in the opposite direction.

6. In a system of the class described, the combination of a track with a vehicle having a controlling mechanism, comprising an element driven from the movement of said vehicle, electric circuits on said vehicle, said mechanism including a frictionally driven disk with a contact member, said disk arranged to control one of said circuits in one position and to control the other circuit in another position and means on said track for operating said mechanism.

7. In a system of the class described, the combination of a track with a vehicle thereon having a controlling mechanism, said mechanism comprising a member driven from the movement of said vehicle to control a circuit when the vehicle moves in one direction and to control a different circuit when the vehicle moves in the opposite direction and also a member continuously driven by the movement of the vehicle for periodically controlling a circuit and means on said track co-operating with said mechanism for con-

trolling the circuit which is periodically controlled.

8. In a system of the class described, the combination of a track divided into blocks with a vehicle thereon having a controlling mechanism controlled by said blocks, said mechanism comprising an element driven by the movement of said vehicle on the track, said element comprising members having directional control according to the direction in which said vehicle moves and controlled by said blocks and other members having uni-directional control controlled by said blocks.

9. In a system of the class described, the combination of a track with a vehicle having a controlling mechanism, comprising an element frictionally driven from the wheel of said vehicle, a directional control operated by said moving element and a unidirectional control connected with said moving element through a lost motion connection and means on said track for operating said mechanism.

10. In a train control system, the combination of a track with a vehicle, and a controlling mechanism on said vehicle comprising a pair of elements moving with said vehicle, one element connected with the other element by a lost motion connection and controlling a circuit on said vehicle.

11. In a system of the class described, the combination of a track with a vehicle having a controlling mechanism, comprising a driving shaft driven from the movement of said vehicle and a controlling shaft driven by said driving shaft, said controlling shaft connected with said driving shaft by idler gears in a frame, said frame capable of changing its position and means on said track for operating said mechanism.

12. In a system of the class described, the combination of a track, a vehicle thereon, an electrically controlled device on said track, a pair of devices on said vehicle responsive to said track device, one of said devices effective at high speed, the other of said devices effective at low speed, both of said devices arranged to produce the same effect on said vehicle.

13. In a system of the class described, the combination of a track, a vehicle thereon, an electrically controlled device on said track, a device on said vehicle receiving an inductive impulse from said track device and another device on said vehicle simultaneously moved by the influence of said track device, said devices arranged to produce the same effects on said vehicle.

14. In a system of the class described, the combination of a track, a vehicle thereon, an electrically controlled device on said track, a device on said vehicle receiving an impulse inductively from said track de-

vice and another device on said vehicle moved independently by said track device, both of said devices arranged to control a circuit on said vehicle.

5 15. In a system of the class described, the combination of a track, a vehicle thereon, a magnet on said track, a device on said vehicle responsive inductively to said magnet and another device responsive magnetically to said magnet, said devices arranged to produce the same effect on said vehicle.

10 16. In a system of the class described, the combination of a track, a vehicle thereon, an electrically controlled device on said track, a plurality of devices on said vehicle responsive to said track device, one of said devices having a maximum effect when running at high speed and the other device having a maximum effect when said vehicle is running at low speed, said devices arranged to control said vehicle.

15 17. In a system of the class described, the combination of a track, a vehicle thereon, having a controlling mechanism, an elongated magnet on said track, a plurality of devices on said vehicle simultaneously responsive to said track magnet, said devices passing equally through the field of said magnet and arranged to give a proceed effect to said controlling mechanism.

20 18. In a train control system, the combination of a track with a vehicle, a magnet on said track, a plurality of devices pivotally suspended at one end from fixed pivots and each independently responsive to said track magnet and operating said controlling mechanism.

25 19. In a system of the class described, the combination of a track, a vehicle thereon, a magnet on each side of said track, a plurality of devices on each side of said vehicle pivoted to swing from one end and means whereby said devices are moved in response to said track magnets to control a circuit.

30 20. In a system of the class described, the combination of a track, a vehicle thereon, an electrically controlled device on each side of said track, a magnetically responsive device pivoted to swing vertically on each side of said vehicle and means whereby said track devices move said pendant devices to establish a circuit in series.

35 21. In a system of the class described, the combination of a track, a vehicle thereon, an electrically controlled device on said track, a plurality of pendant devices on said vehicle responsive to said track device and controlling a circuit, and means whereby said pendant devices when moved in the same direction, prevent the establishment of said circuit.

40 22. In a system of the class described, the combination of a track, a vehicle thereon, an electrically controlled device on said track,

a plurality of pendant devices on said vehicle, independently responsive to said track device and means whereby said devices when simultaneously moved in opposite directions establish a circuit.

45 23. In a system of the class described, the combination of a track, a vehicle thereon, an electrically controlled device on said track, a plurality of pendant devices on said vehicle subject to move under centrifugal action, and means whereby said devices when moving in response to said track device, establish a circuit and when moving in response to said centrifugal action, prevent a circuit from being established.

50 24. In a system of the class described, the combination of a track, a vehicle thereon, an electrically controlled device on said track, a plurality of pendant devices on said vehicle directly responsive to said track device and means whereby when said devices move in opposite directions, a circuit is established and when the position of said devices is reversed another circuit is established.

55 25. In a system of the class described, the combination of a track, a vehicle thereon, a magnet on said track, a controlling mechanism on said vehicle and a plurality of devices on said vehicle pivotally suspended at one end from fixed pivots and each independently responsive to said track magnet and operating said controlling mechanism.

60 26. In a system of the class described, the combination of a track, a vehicle thereon, an electrically controlled device on said track, a controlling mechanism on said vehicle, a plurality of pendant devices directly responsive to said track device and an inductively operated device also responsive to said track device, said pendant devices and inductive device operating said controlling mechanism.

65 27. In a system of the class described, the combination of a track, a vehicle thereon, a magnet on said track having poles parallel to said track, a pair of pendant devices on said vehicle arranged to pass over the plane of said track magnet, said pendant devices consisting of magnetic members with their poles reversed.

70 28. In a system of the class described, the combination of a track, a vehicle thereon, a magnet on said track with poles extending parallel therewith, a plurality of pendant devices on said vehicle passing over the plane of said magnet and means whereby when said magnet is energized, said pendant devices are moved in opposite directions.

75 29. In a train controlling system, the combination of a track with a vehicle thereon having a controlling mechanism, a device on said track, a device on said vehicle associated with said mechanism and controlled by said track device, said vehicle device pivoted with a free movement and subject to centrifugal movement from the swaying of

said vehicle and means for neutralizing the effect of said centrifugal movement on said mechanism.

30. In a system of the class described, the combination of a track with a vehicle thereon, a magnetic member on said track and a magnetic member on said vehicle coacting with said track member, a source of energy on said vehicle for energizing said vehicle member and means controlled by the direction of running of said vehicle for controlling an impulse from said source of energy to said track member.

31. In a system of the class described, the combination of a track, a vehicle thereon, a magnetic member on said track and a magnetic member on each side of said vehicle, and means controlled by the movement of said vehicle for transmitting an effect from one of said vehicle devices to said track member.

32. In a system of the class described, the combination of a track, a vehicle thereon, a magnetic member on said track and a magnetic member on each side of said vehicle and means controlled by the direction of movement of said vehicle for transmitting an effect from one of said vehicle devices to said track member.

33. In a system of the class described, the combination of a track, a vehicle thereon, a controlling mechanism on said vehicle comprising a moving circuit controller driven by the movement of said vehicle arranged to control a plurality of circuits, and a plurality of devices controlled by said circuits, said circuit controller arranged to establish the circuit of one of said devices before interrupting the circuit of the other device.

34. In a system of the class described, the combination of a track, a vehicle thereon, a controlling mechanism on said vehicle comprising a moving circuit controller driven by the movement of said vehicle arranged to control a plurality of circuits, and a pair of relays having a holding circuit controlled by said circuit controller and arranged so that one of said holding circuits is established before the other is interrupted.

35. In a system of the class described, the combination of a track, a vehicle thereon, a controlling mechanism on said vehicle comprising a moving circuit controller driven by the movement of said vehicle over the track, and a plurality of relays having holding circuits controlled by said circuit controller and arranged so that one of said circuits is established in a different portion of track from the other.

36. In a system of the class described, the combination of a track having controlling devices thereon, a vehicle on said track having a controlling mechanism comprising a moving circuit controller driven by the movement of the vehicle over the track, and

a plurality of relays, each having a circuit controlled by said circuit controller, one of said relays controlled by said track device and arranged so that its circuit may be established in the same portion of track in which said track device is located.

37. In a system of the class described, the combination of a track having a controlling device thereon, a vehicle on said track having a controlling mechanism comprising a moving circuit controller driven by the movement of said vehicle over the track, and a plurality of relays controlled by said circuit controller, one of said relays energized from said track device and held energized while the vehicle travels over a definite portion of track and the other relay held energized while the vehicle passes over another portion of track.

38. In a system of the class described, the combination of a track having a controlling device thereon, a vehicle on said track having a controlling mechanism comprising a moving circuit controller driven by the movement of said vehicle, and a plurality of relays controlled by said circuit controller, one of said relays energized from said track device and held energized by said circuit controller while the vehicle moves over a definite portion of track, said relay energizing the other relay which is held energized while the vehicle moves over an additional portion of track.

39. In a system of the class described, the combination of a track with a vehicle thereon having a controlling mechanism with a plurality of circuits, a device on said track, a plurality of devices on said vehicle responsive to said track device and each arranged to control a separate circuit of said mechanism to produce the same effect on said mechanism.

40. In a system of the class described, the combination of a track with a vehicle thereon having a controlling mechanism comprising an element driven by the movement of said vehicle on the track, means on each side of said track co-operating magnetically with means on each side of said vehicle for suspending the operation of said drive and other means on said track for bringing said drive into operation after it has been suspended.

41. In a system of the class described, the combination of a track, a plurality of vehicles thereon, a block controlled device on said track, a controlling mechanism on said vehicles and means for controlling said mechanism by the coupling of said vehicles, by their running direction and by said block controlled device.

42. In a system of the class described, the combination of a track divided into blocks, a plurality of vehicles on said track coupled into a train, a controlling mechanism on each

of said vehicles controlled by said blocks and a circuit controller operated by said block controlled means on said track, a controlling mechanism controlled by said block means and means whereby when a plurality of said vehicles are coupled, said mechanism becomes effective in the leading vehicle when said vehicles move in either direction.

43. In a system of the class described, the combination of a track, a plurality of vehicles thereon coupled into a train, block controlled means on said track, a controlling mechanism controlled by said block means and by the movement of the vehicles on each of said vehicles and means for automatically controlling said mechanism by the direction in which said vehicles move without regard to the arrangement of said block controlled means on the track.

44. In a system of the class described, the combination of a track divided into blocks, a plurality of vehicles on said track forming a train, a controlling mechanism on each of said vehicles controlled by said blocks and by the direction of movement of said vehicle on the track and means whereby said control on any vehicle is affected by the adjacent vehicles of the train.

45. In a system of the class described, the combination of a track, a plurality of vehicles thereon, block controlled means on said track, a controlling mechanism on said vehicles controlled by said block means and means at the ends of each of said vehicles for controlling said mechanism in combination with directional controlled means.

46. In a system of the class described, the combination of a track, a plurality of vehicles thereon, block controlled means on said track, a controlling mechanism on each of said vehicles controlled by said block means, and means whereby, when a plurality of said vehicles are coupled, said mechanism becomes ineffective in all but one of said vehicles.

47. In a system of the class described, the combination of a track, a plurality of vehicles thereon, block controlled means on said track, a controlling mechanism on each of said vehicles controlled by said block means, and means whereby when a plurality of said vehicles are coupled, said mechanism becomes effective in the leading vehicle.

48. In a system of the class described, the combination of a track, a plurality of vehicles thereon, block controlled means on said track, a controlling mechanism on each of said vehicles controlled by said block means and means whereby when a plurality of said vehicles are coupled, said mechanism becomes effective in the leading vehicle when said vehicles move in either direction.

49. In a system of the class described, the combination of a track, a plurality of vehicles thereon coupled to form a train, block controlled means on said track, an independent controlling mechanism on each of

said vehicles controlled by said block means, said mechanism effective on one of said vehicles and means whereby said mechanism automatically becomes effective in each sub-divided unit of said train.

50. In a system of the class described, the combination of a track, a plurality of vehicles thereon coupled to form a train, block controlled means on said track, an independent controlling mechanism on each of said vehicles, normally inactive except on the leading vehicle, controlled by said block means, and means whereby said mechanism automatically becomes effective in the leading vehicle of each sub-divided unit of said train.

51. In a system of the class described, the combination of a track, a plurality of vehicles thereon, block controlled means on said track, a controlling mechanism controlled by said block means on each of said vehicles, comprising elements driven by the movement of said vehicles and means associated with the couplers of said vehicles for suspending the operation of said mechanism.

52. In a system of the class described, the combination of a track, a plurality of vehicles thereon, block controlled means on said track, a controlling mechanism controlled by said block means on each of said vehicles, comprising elements driven by the movement of said vehicles and means associated with the direction of movement of said vehicles for suspending the operation of said mechanism.

53. In a system of the class described, the combination of a track, a plurality of vehicles thereon, coupled to form a train, block controlled means on said track, a controlling mechanism controlled by said block means on each of said vehicles, comprising elements driven by the movement of said vehicles, and means whereby the operation of said mechanism is automatically suspended on the intermediate vehicles forming the train.

54. In a railway traffic controlling system, a track divided into blocks, a vehicle on said track having a controlling mechanism operated by the travel of said vehicle in said blocks to a plurality of fixed controlling positions to retard said vehicle, means on said track controlled by said blocks and means embodied in said mechanism effective while the vehicle travels through substantially half the distance of a block co-operating with said track means for preventing the operation of said controlling mechanism.

55. In a railway traffic controlling system, a track divided into blocks, a vehicle on said track having a controlling mechanism operated by the travel of said vehicle, said mechanism controlling a plurality of stick circuits, translating devices operated by said circuits, and means on said track controlled

by said blocks for energizing one of said translating devices, said device energizing another translating device.

56. In a railway traffic controlling system, a track divided into blocks, a vehicle on said track having a controlling mechanism operated by the travel of said vehicle, said mechanism controlling a plurality of stick circuits, translating devices maintained energized by said circuits when said mechanism is in a predetermined position, means on said track controlled by said blocks for energizing one of said translating devices and said device energizing another translating device.

57. In a railway traffic controlling system, a track divided into blocks, a vehicle on said track having a controlling mechanism operated by the travel of said vehicle to a plurality of fixed controlling positions in an interval of travel less than said blocks and means on said track responsive to said blocks co-operating with said mechanism for preventing the operation of said control during the travel of said vehicle to one of said positions.

58. In a railway traffic controlling system, a track divided into blocks, a vehicle on said track having a controlling mechanism operated by the travel of said vehicle to a plurality of positions to retard said vehicle after a predetermined interval of travel, means on the track controlled by said blocks for preventing said control in one position and means on the vehicle operated by the travel of said vehicle for preventing said control in a position where the track control is not available.

59. In a railway traffic controlling system, a track divided into blocks, a vehicle on said track having a controlling mechanism operated by the travel of said vehicle to a plurality of positions in each of which said vehicle is independently retarded after a predetermined interval of travel, and means on the track controlled by said blocks for preventing said control when said mechanism is operated to one of said positions and co-operating with said mechanism for preventing said control when said mechanism is operated to the other position.

60. In a railway traffic controlling system, a track divided into blocks, a vehicle on said track having a controlling mechanism continuously driven by the travel of said vehicle to a plurality of positions to retard said vehicle, the travel interval of one of said positions being less than one of said blocks, means on the track controlled by said blocks for preventing said control and means on the vehicle for automatically continuing the prevention of said control for a predetermined interval of travel when the vehicle mechanism travels beyond said position.

61. In a railway traffic controlling system,

a track divided into blocks, a vehicle on said track having a controlling mechanism operated by the travel of said vehicle to a plurality of positions to retard said vehicle after predetermined intervals of travel, the travel interval of one of said positions being less than each of the said blocks and the travel interval of two of said positions being approximately equivalent to one of said blocks, means on the track controlled by said blocks for preventing said control in one of said positions and means on the vehicle for continuing the prevention of said control through the travel interval of another of said positions.

62. In a railway traffic controlling system, a track divided into blocks, a vehicle on said track having a controlling mechanism operated by the travel of said vehicle to a plurality of positions to retard said vehicle after predetermined intervals of travel, means on the track controlled by said blocks for preventing said control, effective during the first interval of travel and means on the vehicle for continuing the prevention of said control during the second interval of travel.

63. In a railway traffic controlling system, a track divided into blocks, a vehicle on said track having a controlling device operated by the travel of said vehicle, said device comprising a controlling element driven by a lost motion connection, said connection being substantially equivalent to the travel of one of said blocks and means on the track controlled by said blocks for preventing the control of said vehicle by said controlling element.

64. In a railway traffic controlling system, a track divided into blocks, a vehicle on said track having a controlling mechanism operated by the travel of said vehicle, said mechanism comprising a directional element and also a unidirectional element arranged for movement without regard to the direction of movement of said vehicle and means on the track controlled by said blocks for preventing the control of said vehicle by said mechanism.

65. In a railway traffic controlling system, a track divided into blocks, a vehicle on said track having a controlling mechanism operated by the travel of said vehicle, said mechanism comprising a controlling element arranged for unidirectional movement and driven by a lost motion connection and means on the track controlled by said blocks for preventing the control of said vehicle by said mechanism.

66. In a system of the class described, the combination of a track with a vehicle thereon having a controlling mechanism, a device on said track, and a plurality of devices on said vehicle simultaneously and independently responsive magnetically to said

track device and arranged to control a circuit of said mechanism in series.

67. In a railway traffic controlling system, a track divided into blocks, a vehicle on said track having a controlling mechanism operated by the travel of said vehicle, means on the track controlled by said blocks for preventing the control of said vehicle by said mechanism and means associated with the couplers of said vehicle for suspending the operation of said mechanism.

68. In a railway traffic controlling system, a track divided into blocks, a vehicle on said track having a controlling mechanism operated by the travel of said vehicle, means on the track controlled by said blocks for preventing the control of said vehicle by said mechanism and means controlled by the running direction of said vehicle for suspending the operation of said mechanism.

69. In a railway traffic controlling system, a track divided into blocks, a vehicle on said track having a controlling mechanism operated by the travel of said vehicle, means on the track controlled by said blocks for preventing the control of said vehicle by said mechanism and means associated with the couplers of said vehicle in cooperation with means controlled by the running direction of said vehicle for suspending the operation of said mechanism.

70. In a railway traffic controlling system, a track divided into blocks, a vehicle thereon, a controlling mechanism on said vehicle, a device on said track controlled by said blocks for operating said mechanism and means associated with the couplers of said vehicle for suspending the operation of said mechanism.

71. In a railway traffic controlling system, a track divided into blocks, a vehicle thereon, a controlling mechanism on said vehicle, a device on said track controlled by said blocks for operating said mechanism and means associated with the said couplers cooperating with the running direction of said vehicle for suspending the operation of said mechanism.

72. In a railway traffic controlling system, a track divided into blocks, a vehicle thereon, a controlling mechanism on said vehicle, a device on said track controlled by said blocks for operating said mechanism and means associated with the couplers of said vehicle automatically affecting the operation of said mechanism.

73. In a railway traffic controlling system, a track divided into blocks, a plurality of vehicles thereon, coupled into a train, a controlling mechanism on each vehicle, a device on said track controlled by said blocks for operating said mechanism and means on said vehicles for automatically rendering said mechanism ineffective on all but the leading vehicle.

74. In a railway traffic controlling system, a track divided into blocks, a plurality of vehicles thereon, coupled into a train, a controlling mechanism on each vehicle, a device on said track controlled by said blocks for operating said mechanism and means for automatically suspending the operation of said mechanism on the intermediate vehicles of said train.

75. In a railway traffic controlling system, a track divided into blocks, a plurality of vehicles thereon, coupled into a train, a controlling mechanism on each vehicle, a device on said track controlled by said blocks for operating said mechanism and means for automatically suspending the operation of said mechanism on the intermediate vehicles of said train.

76. In a railway traffic controlling system, a track divided into blocks, a vehicle thereon, a controlling mechanism on said vehicle, a device on said track controlled by said blocks, an electric impulse device and a magnetic impulse device on said vehicle, said electric and magnetic impulse devices responsive to said track device and operating said controlling mechanism.

77. In a railway traffic controlling system, a track divided into blocks, a vehicle thereon, a controlling mechanism on said vehicle, a device on said track controlled by said blocks, an electric impulse device operating without moving parts and a magnetic impulse device operating with moving parts on said vehicle, said devices responsive to said track device and operating said controlling mechanism.

78. In a railway traffic controlling system, a track divided into blocks, a vehicle thereon, a controlling mechanism on said vehicle including a relay having a pick-up circuit, a device on said track controlled by said blocks, and an electric impulse device and a magnetic impulse device on said vehicle responsive to said track device, said impulse and magnetic devices arranged to independently energize the pick-up circuit.

79. In a railway traffic controlling system, a track divided into blocks, a vehicle thereon, a controlling mechanism on said vehicle, a device on each side of said track controlled by said blocks, a pendant device having a free movement pivoted on each side of said vehicle and means whereby, when said pendant devices are co-operatively moved in a predetermined direction by said track devices, the operation of said mechanism is suspended.

80. In a railway traffic controlling system, a track divided into blocks, a vehicle thereon, a controlling mechanism on said vehicle having a retarding and non-retarding condition, a device on said track controlled by said blocks, and a plurality of magnetic devices responsive to said track device, said

devices when moved in opposite directions, arranged to produce a non-retarding condition on said mechanism.

81. In a railway traffic controlling system, a track divided into blocks, a vehicle thereon, a controlling mechanism on said vehicle having a retarding and a non-retarding condition, a device on said track controlled by said blocks, and a plurality of magnetic devices responsive to said track device, said devices when moved in opposite directions arranged to produce a non-retarding condition in said mechanism and when moved in the same direction being ineffective in controlling said mechanism.

82. In a railway traffic controlling system, a track divided into blocks, a vehicle thereon, a controlling mechanism on said vehicle having a relay with a pick-up circuit, a device on said track controlled by said blocks, and a plurality of magnetic devices responsive to said track device, said devices arranged when moved in opposite directions to energize said pick-up circuit.

83. In a railway traffic controlling system, a track divided into blocks, a vehicle thereon, a controlling mechanism on said vehicle having a retarding and a non-retarding condition, a device on said track controlled by said blocks, and a plurality of pendant devices, responsive to said track device, said devices arranged to move in opposite directions to produce a non-retarding condition in said mechanism.

84. In a railway traffic controlling system, a track divided into blocks, a vehicle thereon, a controlling mechanism on said vehicle, having a retarding and a non-retarding condition, a device on said track controlled by said blocks, a plurality of pendant devices responsive to said track device, said devices when moved in opposite directions arranged to produce a non-retarding condition on said mechanism and when moved in the same direction being ineffective in controlling said mechanism.

85. In a railway traffic controlling system, a track divided into blocks, a vehicle thereon, a controlling mechanism on said vehicle, a device on each side of said track controlled by said blocks, a device pivoted on each side of said vehicle and capable of being moved magnetically to a plurality of positions by said track devices and means whereby said mechanism is controlled when said vehicle devices are co-operatively moved to predetermined positions.

86. In a railway traffic controlling system, a track arranged for traffic in both directions and divided into blocks, a vehicle on said track, a controlling mechanism on said vehicle, a device on said track controlled by said blocks, a device on said vehicle responsive to said track device, operating said mechanism, and means on said track where-

by opposing traffic is prevented and a second device on the track cooperating with means on said vehicle whereby following traffic is permitted according to the spacing of said block system.

87. In a railway traffic controlling system, a track divided into blocks, and controlled by a block system for traffic in both directions, a vehicle on said track, a controlling mechanism on said vehicle, a device on said track controlled by said block system, a device on said vehicle responsive to said track device operating said mechanism and means on the track at intervals responding to the passage of a vehicle for automatically permitting following traffic according to the spacing of said block system.

88. In a railway traffic controlling system, a track divided into blocks, and controlled by a block system for traffic in both directions, a vehicle on said track, a controlling mechanism on said vehicle, a device on said track controlled by said block system, a device on said vehicle responsive to said track device operating said mechanism and means on one side of said track responding to the passage of a vehicle for permitting following traffic.

89. In a railway traffic controlling system, a track divided into blocks, and controlled by a block system for traffic in both directions, a vehicle on said track, a controlling mechanism on said vehicle controlled by said block system, a device on said vehicle responsive to said track device operating said mechanism and means on one side of said track responding to the passage of a vehicle for permitting following traffic.

90. In a railway traffic controlling system, a track divided into blocks, and controlled by a block system for traffic in both directions, a vehicle on said track, a controlling mechanism on said vehicle, a device on said track controlled by said block system, a device on said vehicle, responsive to said track device operating said mechanism and means on the track at intervals inductively responding to the passage of a vehicle for permitting following traffic according to the spacing of the block system.

91. In a railway traffic controlling system, a track divided into blocks, and controlled by a block system for traffic in both directions, a vehicle on said track, a controlling mechanism on said vehicle, a device on said track controlled by said block system, a device on said vehicle responsive to said track device operating said mechanism, means on the track at intervals and means on said vehicle controlled by the running direction of said vehicle cooperating with said track means for permitting following traffic according to the spacing of the block system.

92. In a railway traffic controlling system, a track divided into blocks, and controlled

5 by a block system for traffic in both directions, a vehicle on said track, a controlling mechanism on said vehicle, a device on said track controlled by said block system, and
10 a device on said vehicle responsive to the running direction of said vehicle for permitting following traffic according to the spacing of the block system.

15 93. In a railway traffic controlling system, a track arranged for traffic in both directions, a block system controlling said traffic, a vehicle on said track, a controlling mechanism on said vehicle, a device on said track controlled by said block system, a device on said vehicle responsive to said track device operating said mechanism, said block system arranged to prevent traffic in opposite directions, a stick relay associated with said block system for permitting following traffic spaced according to said block system, and means on said vehicle for energizing said relay.

20 94. In a railway traffic controlling system, a track arranged for traffic in both directions, a block system controlling said traffic, a vehicle on said track, a controlling mechanism on said vehicle, a device on said track controlled by said block system, a device on said vehicle responsive to said track device operating said mechanism, said block system arranged to prevent traffic in opposite directions, a stick relay associated with said block system for permitting following traffic spaced according to said block system and means on said vehicle controlled by its running direction for energizing said relay.

25 95. In a railway traffic controlling system, a track arranged for traffic in both directions, a block system controlling said traffic, a vehicle on said track, a controlling mechanism on said vehicle, a device on said track controlled by said block system, a device on said vehicle responsive to said track device operating said mechanism, said block system arranged to prevent traffic in opposite directions, a stick relay associated with said block system for permitting following traffic spaced according to said block system and means on one side of said track responsive to the passage of said vehicle for energizing said relay controlling traffic in one direction.

30 96. In a railway traffic controlling system, a track arranged for traffic in both directions, a block system controlling said traffic, a vehicle on said track, a controlling mechanism on said vehicle, a device on said track controlled by said block system, a device on said vehicle responsive to said track device operating said mechanism, said block system arranged to prevent traffic in opposite directions, a stick relay associated with said block system for permitting following traffic spaced according to said block system, and means on one side of said track controlling

35 said relay for traffic in one direction and means on the opposite side of said track controlling said relay for traffic in the opposite direction, said track means being responsive to the passage of a vehicle in the established direction of traffic.

40 97. In a railway traffic controlling system, a track arranged for traffic in both directions, a block system controlling said traffic, a vehicle on said track, a controlling mechanism on said vehicle, a device on said track controlled by said block system, a device on said vehicle responsive to said track device operating said mechanism, said block system arranged to prevent traffic in opposite directions, a stick relay associated with said block system for permitting following traffic spaced according to said block system, and means on said vehicle for inductively energizing said relay.

45 98. In a railway traffic controlling system, a track divided into blocks, a vehicle on said track having a controlling mechanism operated from the running gear of said vehicle on the track, means on said track controlled by said blocks affecting the operation of said mechanism and means whereby said vehicle may back up on said track for a distance equal substantially to one of said blocks without affecting said mechanism.

50 99. In a railway traffic controlling system, a track divided into blocks, a vehicle on said track having a controlling mechanism operated by the travel of said vehicle on the track, means on said track controlled by said blocks affecting the operation of said mechanism and means whereby said vehicle may back up at any position on said track for a limited distance without affecting said mechanism.

55 100. In a railway traffic controlling system, a track divided into blocks, a vehicle on said track having a controlling mechanism continuously driven by the travel of said vehicle on the track and arranged to control said vehicle, means on said track controlled by said blocks affecting the control of said vehicle and means whereby said vehicle may back up on said track at any point for a distance corresponding to one of said blocks without affecting said mechanism and resume its normal running direction without changing the conditions of said mechanism relative to said track means.

60 101. In a railway traffic controlling system, the combination, a track divided into blocks, a vehicle on said track having a mechanism continuously driven by the travel of said vehicle and arranged to control said vehicle, means on said track controlled by said blocks affecting the control of said vehicle and means whereby the normal operation of said mechanism by the travel of said vehicle is suspended at any position in the

block when said vehicle changes its running direction.

102. In a railway traffic controlling system, the combination, a track divided into 5 blocks, a vehicle on said track having a mechanism operated by the travel of said vehicle and arranged to control said vehicle, means on said track controlled by said blocks affecting the control of said vehicle and 10 means whereby the normal operation of said mechanism by the travel of said vehicle is suspended at any position in the block for a limited distance of travel of the vehicle when it changes its running direction and 15 is resumed when this limited distance is exceeded.

103. In a railway traffic controlling system, the combination, a track divided into 20 blocks, a vehicle on said track having a mechanism operated by the travel of said vehicle and arranged to control said vehicle, means on the track controlled by said blocks affecting the control of said vehicle and 25 means whereby, at any position in the block, the operation of said mechanism by the travel of said vehicle is suspended for a pre-determined distance of travel when the vehicle changes its running direction and means 30 whereby said operation is resumed when said predetermined distance is exceeded.

104. In a system of the class described, the combination of a track with a vehicle thereon having a controlling mechanism, a device on said track electrically energized, a plurality of devices on said vehicle free to swing at right angles to the plane of movement of said vehicle, said devices magnetically responsive to said track device and operating said mechanism.

105. In a system of the class described, the combination of a track with a vehicle thereon having a controlling mechanism, a magnet on said track, a plurality of devices on said vehicle secured by fixed pivots to swing from one end, each of said vehicle devices being independently responsive to said track magnet and operating said mechanism.

106. In a system of the class described, the combination of a track with a vehicle thereon having a controlling mechanism, a device on said track, and a plurality of pivoted magnets on said vehicle independently responsive to said track device and arranged 55 to operate said mechanism to produce the same effect on said mechanism.

107. In a system of the class described, the combination of a track with a vehicle thereon having a controlling mechanism, a device on said track for operating said mechanism and a pair of pivoted magnets with their poles reversed associated with said mechanism.

108. In a system of the class described, the 65 combination of a track with a vehicle there-

on having a controlling mechanism, means on said track for operating said mechanism and a stationary magnet and a plurality of pivoted magnets with their poles reversed associated with said system.

70

109. In a system of the class described, the combination of a track with a vehicle thereon having a controlling mechanism, means on said track for operating said mechanism, a pivoted device associated with said mechanism and subject to centrifugal action by movement of said vehicle other than that obtained from the running wheels of the vehicle and means for preventing said centrifugal action from affecting said mechanism.

80

110. In a system of the class described, the combination of a track with a vehicle thereon having a controlling mechanism, a magnet on said track, a translating device associated with said mechanism and a plurality of independent means for energizing said translating device, said means inductively responsive to said track magnet.

85

111. In a system of the class described, the combination of a track with a vehicle thereon having a controlling mechanism, said mechanism comprising a moving circuit controller controlling a plurality of circuits in timed relation so that one circuit is established before the other is interrupted, said 90 circuits controlling said vehicle.

90

112. In a system of the class described, the combination of a track with a vehicle thereon having a controlling mechanism, means on said track for controlling said mechanism, a plurality of circuits on said vehicle associated with said mechanism, said mechanism comprising means for controlling said 100 circuits in timed relation so that one circuit is established before the other is interrupted.

105

113. In a system of the class described, the combination of a track with a vehicle thereon having a controlling mechanism, a device on each side of said track and a plurality of devices fixedly pivoted at one end on each side of said vehicle independently responsive to said track devices for co-operatively operating said controlling mechanism.

110

114. In a system of the class described, the combination of a track with a plurality of vehicles thereon coupled into a train, controlling means on said track, a controlling mechanism responsive to said track means on each vehicle, a circuit controller on each vehicle arranged to suspend the operation of said mechanism and means for automatically operating said circuit controller when said vehicles are coupled.

115

115. In a system of the class described, the combination of a track with a plurality of vehicles thereon coupled to form a train, a controlling mechanism on each vehicle, a circuit controller operated by the movement of the vehicle on the track, a circuit controlled by the couplings of said vehicle and con-

120

125

130

trolling said mechanism, means for operating said mechanism selectively by said circuit controller depending upon the direction of movement of said train and means on the 5 track controlling said mechanism.

116. In a system of the class described, the combination of a track with a vehicle thereon, a controlling mechanism on said vehicle operated by the movement of the vehicle on the 10 track, means on the track for controlling said mechanism, a circuit controller on said vehicle operated by the movement of the vehicle on the track and means for suspending the operation of said mechanism selectively, by said circuit controller depending upon the direction of movement of said vehicle.

117. In a train controlling system, the combination of a track with a vehicle thereon having a controlling mechanism, a device on said track, and a plurality of pendant devices on said vehicle fixedly pivoted and capable of independent action and magnetically responsive to said track device, a circuit 20 controlling said mechanism, said circuit controlled in series by said pendant devices.

118. In a railway traffic controlling system, a track arranged for traffic in both directions, a block system controlling said 30 traffic, a vehicle on said track having a mechanism controlled by said block system, said block system comprising directional relays for establishing the direction of traffic and stick relays for releasing the block for 35 following traffic, and a plurality of trans-

lating devices on said vehicle selectively operative to energize said stick relay.

119. In a railway traffic controlling system, a track arranged for traffic in both directions, a block system controlling said 40 traffic, a vehicle on said track having a mechanism controlled by said block system, a stick relay associated with said block system and controlling traffic in the established direction and a device on said vehicle selectively operative to energize said relay as said vehicle changes its running direction. 45

120. In a system of the class described, the combination of a track divided into blocks, a vehicle on said track having a controlling 50 mechanism including a plurality of block relays responsive to the block conditions of said track, a magnet for suspending the operation of said mechanism and means on the track co-operating with said block relays in 55 the deenergized position for maintaining said magnet in condition for suspending said operation.

121. In a system of the class described, the combination of a track divided into blocks, 60 a vehicle on said track having a controlling mechanism including a plurality of block relays responsive to the block conditions of said track, a magnet for suspending the operation of said mechanism when energized, 65 means for energizing said magnet and means whereby said magnet is maintained energized by said block relays in the deenergized position.

MATTHEW H. LOUGHridge.
